UNITED STATES PATENT OFFICE.

ALFRED F. PAPIN, OF YONKERS, NEW YORK, ASSIGNOR TO CHENEY BROTHERS, OF SOUTH MANCHESTER, CONNECTICUT, A CORPORATION OF CONNECTICUT.

DESIGN FOR A TEXTILE FABRIC.

No. 38,594.

Specification for Design.

Patented May 28, 1907.

Application filed May 6, 1907. Serial No. 372,287. Term of patent 3½ years.

To all whom it may concern:

Be it known that I, ALFRED F. PAPIN, a citizen of the United States, residing at the city of Yonkers, Westchester county, State of New York, have invented a new, original, and ornamental Design for Textile Fabrics, of which the following is a specification, reference being had to the accompanying drawing, forming part thereof.

The figure is a plan view of the fabric, showing my new design.

I claim:

The ornamental design for a textile fabric, as shown.

ALFRED F. PAPIN.
